UNITED STATES PATENT OFFICE.

SAMUEL J. CLISE, OF MIDLAND, MARYLAND.

SCRUBBING-MACHINE.

SPECIFICATION forming part of Letters Patent No. 643,469, dated February 13, 1900.

Application filed May 28, 1897. Serial No. 638,611. (No model.)

To all whom it may concern:

Be it known that I, SAMUEL J. CLISE, of Midland, in the county of Allegany and State of Maryland, have invented certain new and useful Improvements in Scrubbing-Machines; and I do hereby declare the following to be a full, clear, and exact description of the invention, such as will enable others skilled in the art to which it appertains to make and use the same.

My invention relates to improvements in scrubbing-machines; and its object is to provide a machine of this character with improved scrubbing mechanism whereby a floor may be readily and expeditiously cleaned.

With this and other objects in view the invention consists in the novel constructions and combinations of parts hereinafter more fully described and specifically set forth in the appended claims.

In the accompanying drawings, illustrating the invention, Figure 1 is an elevational view of a scrubbing-machine embodying my invention looking toward the right side thereof. Fig. 2 is a broken detail view of the adjusting mechanism for raising the drying-roller and receptacle. Fig. 3 is an enlarged detail view, partly in section and partly in elevation, of the clutch connection for throwing the sprocket-wheel on the auxiliary drive-shaft into and out of operation. Fig. 4 is a longitudinal sectional view of the scrubbing-machine. Fig. 5 is a broken detail view showing the catch for retaining the sliding receptacle in position. Fig. 6 is a broken detail sectional view illustrating the latch mechanism of the connecting-rod. Fig. 7 is a top plan view of the scrubbing-machine. Fig. 8 is a broken detail perspective view of one end of the drive-shaft and the bearing-bracket in which it is mounted. Fig. 9 is a front elevational view of the machine. Fig. 10 is a side elevational view showing a portion of the frame of the brush mechanism proper and the drying-roller and receptacle connected therewith. Fig. 11 is a cross-sectional view showing the ratchet connection of the main drive-sprocket. Fig. 12 is a side elevational view showing the intermeshing gears of the crank-shaft and auxiliary drive-shaft. Fig. 13 is a detail view illustrating the flap connections of the drying-roller.

Like numerals of reference designate corresponding parts throughout the several figures of the drawings.

55

Referring now more particularly to the accompanying drawings, the numeral 1 designates the frame of the scrubbing-machine, which comprises two side bars 2, a cross-bar 3, connecting the side bars 2 at the rear of the frame, and a metal plate or connecting-bar 3^a, extending across at the front of the frame and connecting the front ends of the side bars. This bar is provided with two spaced upwardly-projecting loops or offsets 65 4 and a handhold 5 between said offsets to afford means for raising the front end of the frame. The side bar 2 at the left-hand side of the machine is provided at the front and at the under side thereof with a cut-away 70 space or recess 2^a, through which the end of the scrubbing-brush frame projects, as will be hereinafter described.

Projecting upwardly from the side bars of the frame at the rear thereof are standards 6, 75 provided at the upper ends thereof with notches for the reception of the bearing-blocks 7, each of the said blocks being formed with a vertical slot 7^a for the passage of a confining-bolt 8, this construction of parts enabling 80 the said bearing-blocks to be adjusted as desired. Braces 9 may be provided to assist in sustaining the bearing-standards, if desired. Connected with these standards at the upper end thereof is a handle-frame 10, consisting 85 of two side arms or supports 11 and a transverse handle 12.

Connected with the side standards 2 on the inner side thereof and at the front of the frame are slide-rods 13, on which the brush-carrier 90 frame is adapted to reciprocate. The brush-frame comprises a metallic plate 14, to which a board 15, carrying the brushes, is secured, said plate being provided with upwardly-projecting pins 16. The brush-board is provided 95 with a lateral extension 15^a, which projects through the recess or cut-away space 2^a at the under side of the side bar at the left-hand side of the frame a sufficient distance outward from said side bar to enable the machine 100 to be operated for scrubbing the floor close to a side wall or other obstruction. On the metallic plate 14 is mounted a spider-bearing frame 17, formed with a central cross-bar or

body portion 17^a and a series of arms 17^b, radiating therefrom and provided with eyes or bearing projections 17^c, which engage the slide-rods 13. These arms are also provided 5 adjacent said bearing projections with enlargements formed with openings 17^d, through which the pins 16 on the metallic brush-carrying plate project loosely. An adjusting-screw 18 operates in the threaded opening in 10 the body portion 17^a of the spider-bearing frame and also in the threaded socket in the metallic brush-carrying plate 14, a coil-spring 19, surrounding said arm, being provided to maintain the parts in proper relation. By 15 this construction it will be seen that the brush mechanism may be adjusted in a vertical plane as desired, and that, as the brush-frame is not rigidly secured at any point, provision is made whereby one portion thereof 20 may give or yield in a vertical plane to compensate for irregularities or undulations in the surface of the floor and to enable the brush mechanism to clear any obstruction which may be encountered without injury 25 thereto, this being effected by the pin 16 moving loosely in the openings 17^d, the adjusting-screw 18 yielding slightly to permit of this movement.

The frame 1 is mounted at the rear upon 30 rollers 20 and at the front upon rollers 21. The rollers 21 are mounted in bearing-brackets 22, and I have constructed and arranged the frame and bearing-brackets in such manner as to permit of the front of the frame being 35 adjusted as desired to raise the brush-carrying frame either entirely out of contact with the floor or in contact therewith and to regulate the pressure of the brushes upon the floor independent of the adjusting-screw 18, 40 heretofore described. To this end the brackets 22 slide vertically in openings in the front end of the side bars 2 and are connected at their upper ends by a cross-bar 23, which has position above the front ends of the side bars, 45 as shown in Figs. 1 and 4, and is secured to the ends of the roller-brackets in any suitable manner. An oscillatory adjusting-shaft 24 is positioned between the cross connecting-bars 3^a and 23 and is mounted in bearing projections 25, secured upon the former, and the end 24^a of this shaft extends outward at one side of the frame, as shown. This oscillatory 50 adjusting-shaft 24 carries two cam-disks 26, which occupy the loops or offsets 4 of the connecting-bar 3^a and are adapted to bear upon the bar 23. When the shaft 24 is turned so as to force that portion of the periphery of the cam-disks which is farthest therefrom to bear upon the connecting-bar 23, the latter 55 is forced down and carries with it the bearing-brackets, and the front end of the frame is forced up and the brush mechanism raised out of contact with the floor. In order to effect this operation, I have provided an adjusting-lever 27, pivotally mounted upon one 60 of the braces 9 and having its lower end connected by means of a rod 28 with the later-

ally-projecting end 24^a of the adjusting-shaft 24, as shown. This lever is provided with a spring-pressed pawl 29, adapted to engage the 70 teeth of a segment-rack 30, so as to secure the parts and hold them in the position to which they have been adjusted. The connecting-rod and the shaft may be limited in their throw or movement by stops 28^a on the ad- 75 joining side bar 2 of the frame.

A drive-shaft 31 is mounted in the bearing-blocks 7 of the standards 6 and carries a drive-sprocket 32, said sprocket having a portion of its hub 33 formed with rack-teeth, with 80 which a spring-pressed pawl 34 is adapted to engage to prevent the said shaft from being turned rearwardly, while readily permitting it to be revolved in the reverse direction, the pawl sliding over the teeth during this latter 85 operation.

35 designates a crank-shaft mounted in bearings in the side bars 2 of the frame and having its ends projecting exteriorly thereof. This shaft is provided at one end of its central 90 crank portion 35^a with a balance-wheel 36 and at the other side with a sprocket-wheel 37, which receives power from the drive-sprocket 32 by means of a chain 37^a. The adjustability of the bearing-blocks 7 permits of the drive-shaft and drive-sprocket being adjusted to 95 take up any slack in the chain 37^a. The crank-shaft is also provided adjacent the sprocket 37 with a pinion 38, which meshes with a pinion 39, mounted on one end of an auxiliary drive-shaft 40, revolvably mounted in a bearing-bracket 41 and bearings in the side bar 2 at the right-hand side of the machine. The outer end of this auxiliary drive-shaft is formed with a square head 42 and a 100 threaded terminal 43, said square head being adapted to receive a clutch disk or collar 44, provided with an opening 45, and the threaded terminal end 43 being adapted to receive a nut 46, which is adapted to confine the said 105 clutch-disk thereon. A sprocket-wheel 47 is loosely mounted on said shaft and is provided with a bolt or connecting-pin 48, operating in a slot 49 therein and adapted to be projected to engage the opening 45 in the clutch-disk, and thereby rigidly connect the said 110 sprocket-wheel with the shaft and cause it to be revolved therewith. The slot 49 is provided with two lateral offsets 49^a 49^b, and the bolt is formed with a pin 48^a, which is adapted 115 to fit in either one of said offsets. By means of said pin the bolt 48 may be thrown into and out of engagement with the clutch-disk 44 and held in said position. When the pin occupies the lateral offset 49^a, the bolt is projected and rigidly connects the sprocket with the clutch-disk; but when occupying the offset 49^b it disconnects the sprocket from said 120 disk and leaves the said sprocket free, so that the shaft may be turned independently 125 thereof.

The brush mechanism is adapted to be reciprocated by means of the crank-shaft through suitable connections therewith. In

the present instance I have provided a connecting-rod 50, pivoted at one end between two ears 51 on the spider-bearing frame 17 and formed at its other end with an engaging hook 52, adapted to engage the offset or crank portion 35^a of the crank-shaft 35 and provided with a socket or opening 53 for the reception of a tongue 54 on the sliding latch or keeper bar 55, said bar being provided with a 10 clamping-screw 56 to engage the shaft and retain the connecting-bar in position thereon. This latch-bar is mounted to slide on the connecting-bar by means of confining-screws 57, projecting through slots 58 therein and entering threaded openings in the connecting-bar, as clearly shown in Fig. 6. By this mode of connection the connecting-bar may be quickly and conveniently thrown into and out of engagement with the crank-shaft. 15 When the machine is not in operation, the connecting-bar 50 is adapted to be thrown forward and locked in position by means of the latch mechanism just described upon the handhold 5 of the connecting-bar 3^a at the front of the frame. By the mechanism hereinbefore described it will be seen that by operating the drive-shaft 31 through the medium of its crank-handle the brush mechanism may be reciprocated rapidly on the slide- 20 rods 13, so as to quickly and effectively scrub the floor.

In the operation of the device it will be understood that the floor is first watered and soaped as desired independent of the machine, 25 although I may provide the machine with a water-reservoir and suitable means for employing soap or any other desired cleansing agent or compound.

The scrubbing-machine is also provided 30 with drying mechanism of novel construction, adapted to dry the floor after the scrubbing operation has been effected. To this end I have provided a three-sided drying-frame 59, the side arms 60 of which have their inner 35 ends adjustably mounted in bearing-brackets 61, secured upon the outer projecting end of the crank-shaft 35 and retained thereon by a bolt-and-nut connection 62. This frame is provided at the rear with a transverse sup- 40 porting bar or plate 63, depending therefrom and suitably connected therewith and adapted to receive a receptacle 64, in which the wa- 45 ter taken up from the floor is adapted to be received. This receptacle is adapted to be 50 slid into and out of the frame and supported by the said plate or bar 63. In order to hold the receptacle in position, I have provided the rear cross-bar 60^a of the frame with a spring- 55 actuated detent or latch 65. Mounted in this 60 frame upon a shaft 66 is a drying-roller 67, which projects transversely of the frame, at the rear thereof, and has one end extended beyond the line of the side bar 2 of the frame at the left-hand side of the machine in line 65 with the lateral extremity 15^a of the scrub- 65
bing-brush. This drying-roller is of novel construction and consists of a roller proper,

66^a, of wood or other suitable hard material to give body and strength thereto. Around this roller is a covering or sheathing 68, of 70 sheet-rubber or other suitable waterproof material, and covering this rubber a layer of absorbent cotton or other suitable material of this character 69, which is adapted to absorb moisture and is yielding or compressible to 75 permit the roller to give or yield when encountering an obstruction or inequalities or undulations of surface in the floor without affecting the other portions thereof. An outer layer of canvas 70 or other suitable material 80 which possesses a certain amount of rigidity, with sufficient elasticity, incloses the absorbent material and is provided around the circumference thereof at regular intervals with a series of flaps 71. These flaps form between 85 them pockets to receive and confine the water taken up from the surface of the floor and are formed by lapping the canvas or other material employed and uniting said lapped portions by stitching 72, as illustrated in Fig. 13. 90 These flaps project tangentially in the same direction and are adapted to take or scoop up the water from the surface of the floor and carry it around until the receptacle 64 is reached, whereupon the water will begin to 95 run out of the said pockets formed by the flaps and into the said receptacle.

In order to insure that all the water taken up by the roller and absorbed by the absorbent material 69 may be discharged from the 100 roller, I have provided mechanism adapted to bind against the periphery of the said roller and express the water therefrom and conduct it to the said receptacle 64. To this 105 end the drier-frame is provided with two segment-shaped arms 73, one arranged at each side of the frame, said arms having their ends adjoining the scrubbing-frame pivoted at 74 to the side arm 60 of the drier-frame and provided at said end with a lip or projection 75. 110 The arms are connected by transverse connecting-rods 76. Pivoted to the rear ends of these rods is a transversely-arranged blade or bar 77, provided with a beveled edge 78, adapted to bear upon the periphery of the 115 roller and force the water out of the pockets formed by the flaps 71 and also express the water which may have been absorbed by the absorbent material 69. This blade or bar is arranged at an inclination above the mouth 120 or opening 64^a of the receptacle 64, and the water from the roller flows down upon the said bar or blade and enters the said receptacle, which latter may be removed when full and emptied. In order to cause the blade 77 to 125 bear firmly against the roller, I have provided a lever 73, Fig. 7, pivoted to the arms 60 by a pivot-bolt 80 and having two angularly-arranged ends, one of which bears against the under side of said lip-projection 75 of the 130 segment-arms 73, and is adapted to force the said lips upward, so as to cause the transverse blade or bar to bear firmly against the periphery of the roller. An adjusting-screw

81, operating in a bearing-bracket 82, is adapted to bear against the opposite end of the adjusting-lever to accomplish this result. To effect a further adjustment of the pivoted bar or blade independent of the segment-arms 73, I have provided the inner end of each segment-arm 73 with an adjusting-piece 83, pivoted thereto by a pivot-bolt 84 and having a loop-shaped end 85 secured to the 5 lower end of the clearing-blade 77 and a rearwardly-projecting bearing-lip 86, (see Figs. 4 and 10,) forming the opposite end of the adjusting-piece, arranged at the other side of the blade. Adjusting-screws 87, operating in bar projections 88, are adapted to bear on said lips and cause the said loop-shaped ends to be forced inwardly, so as to press the cleaing-blade against the roller. By this means, when the limit of adjustment of the 10 segment-arms has been reached the clearing-blade may be further adjusted independently thereof to bear with any desired degree of pressure against the periphery of the drive-roller.

15 25 In order to lift the drying-roller and its frame out of contact with the floor when the machine is not in use and is being transported from one place to another, I have provided a shaft 89, having bearings in the two side 20 arms 11 of the handle-frame and extending parallel with the handle 12. This shaft carries a pawl 90 and two forwardly-projecting arms 91, which are connected with the pivoted arm 60 of the drier-frame by connecting-rods 30 35 40 45 50 55 60 65 70 75 80 85 90 95 100 105 board provided with bearings engaging said slide-rods, a crank-shaft, mechanism for driving the same, and a connecting-rod pivoted at one end to the brush-board and provided at the other end with a hook to engage the said crank-shaft, and a latch to confine it thereon, substantially as described.

7. In scrubbing-machines, the combination of a frame provided with slide-rods, a brush-board, a bearing-spider adjustably connected therewith and provided with bearings engaging said slide-rods, a crank-shaft, means for driving the same, a connecting-rod pivoted at one end to the said spider and formed at its other end with a hook to engage the crank-shaft and with a groove or slot, and a sliding latch on said board provided with a tongue to engage said groove and a thumb-screw to engage the shaft and secure the rod thereon, substantially as described.

8. In scrubbing-machines, the combination of a frame provided with slide-rods and at the front with a handhold, a scrubbing-board provided with bearing projections to engage said slide-rods, means for effecting the vertical adjustment of the scrubbing-board relative to said rods, a crank-shaft, means for driving the same, a connecting-rod pivoted to the brush-board at one end and provided at the opposite end with a hook to engage the shaft, and a latch to retain it thereon, said rod being adapted to be disengaged with the crank-shaft and engaged with the said handhold when the machine is out of use, substantially as described.

9. In scrubbing-machines, the combination of a frame provided with slide-rods, a brush-board provided with bearing projections engaging said slide-rods, means for effecting the vertical adjustment of the brush-board independently of the frame, further means for adjusting the front end of the frame independently of the brush-board, and means for imparting reciprocating motion to the brush-board, substantially as described.

10. In scrubbing-machines, the combination of a frame provided with slide-rods, a brush-board provided with bearing projections engaging said slide-rods, roller-bearing brackets at the front end of the frame movable in vertical slots therein, a bar connecting the upper end of said brackets, and a shaft provided with cam-disks adapted to bear upon said bar to adjust the front end of the frame independently of said brush-board, substantially as described.

11. In scrubbing-machines, the combination of a frame, roller-brackets at each end of the frame vertically movable in slots therein, a cross-bar connecting the upper ends of said brackets, a reciprocating brush-board, a shaft extending across the front of the frame and provided with cam-disks to engage said cross-bar to lift the front end of the frame on said roller-brackets, an adjusting-lever, a connection between the said adjusting-lever and the cam-disk lever, and means for holding

the adjusting-lever immovable, substantially as described.

12. In scrubbing-machines, the combination of a frame, roller-brackets at the front end of the frame movable in vertical slots therein, a bar extending across the front of the frame and connecting the two side boards thereof, said bar provided with two vertical lips or offset portions and a handhold, a reciprocating brush-board, an oscillatory shaft provided with cam-disks adapted to bear on the front end of the bar connecting the roller-brackets to lift the front end of the frame, a rock-shaft, and a connecting-rod pivoted at one end to the brush-board and having its other end adapted to engage either the crank-shaft or the said handhold, substantially as described.

13. In a scrubbing-brush, the combination of a frame provided with slide-bars, a brush-board reciprocating on said slide-bars, a crank-shaft provided with a sprocket, a connecting-rod connecting between the brush-board and crank-shaft, a drive-shaft provided with a sprocket and a crank-handle, and a chain communicating between the said sprockets, substantially as described.

14. In scrubbing-machines, the combination of a frame provided with slide-rods, a brush-board provided with brushes and bearing projections engaging said slide-rods, a crank-shaft, a drive-shaft, connections between said two shafts, a drying-roller in rear of the frame, and connections between the said drying-roller and the crank-shaft for revolving the former, substantially as described.

15. In a scrubbing-machine, the combination of a frame provided with slide-rods, a brush-board carrying brushes, a spider-bearing adjustably secured to said brush-board and provided with radial arms having bearing projections engaging the said slide-rods, a crank-shaft, a connecting-rod pivoted to said spider-bearing and having its other end detachably connected with the crank-shaft, roller-brackets operating in vertical openings in the side bars at the front of the frame, a bar connecting the said roller-brackets at the top, an oscillatory shaft provided with cam-disks adapted to bear on said connecting-bar to adjust the front end of the frame, a lever pivoted to the frame and provided with a pawl adapted to engage a rack-bar thereon, and a rod connecting the adjusting and oscillatory levers, substantially as described.

16. In scrubbing-machines, the combination of a frame provided with slide-rods, a brush-board reciprocating thereon, a drive-shaft, a crank-shaft connected with the said brush-board and provided with a pinion, a connection between the drive and crank shafts, an auxiliary drive-shaft provided with a pinion meshing with the pinion on the crank-shaft, said crank-shaft being provided with a squared head and a threaded extremity, a sprocket-wheel mounted on said auxil-

ary shaft and provided with a locking-bolt, a clutch-disk fitted on the squared head of the shaft provided with an opening to receive the bolt to rigidly mount the sprocket on said 5 shaft, a nut on the threaded end of the auxiliary shaft confining the clutch-disk thereon, a bearing-roller mounted on the shaft at the rear of the brush-frame, said shaft being provided with a sprocket, and a chain connect- 10 ing the said sprocket and the sprocket on the auxiliary shaft, substantially as described.

17. In scrubbing-machines, the combination with a frame, brush mechanism, and means for driving the same, of a drying-roller 15 in rear of the said frame and driven by said mechanism, said drying-roller having an outer layer of fabric folded or lapped upon itself to form a series of longitudinally-extending, tangentially-arranged flaps forming pockets 20 or recesses between them to receive the dirt and water from the floor, substantially as described.

18. In scrubbing-machines, the combination with a frame, scrubbing-brushes, and 25 means for driving the same, of a roller in rear of said frame driven by said mechanism, said roller having a cover or sheathing of waterproof material, a layer of absorbent material inclosing said waterproof material, and an 30 outer layer of fabric folded or lapped upon itself to form a series of tangentially-arranged, longitudinally-extending flaps forming pockets or recesses, substantially as described.

35 19. In scrubbing-machines, the combination of a frame, scrubbing mechanism, means for driving said scrubbing mechanism, a drier-frame in rear of said scrubbing-frame and provided with a receptacle, a roller revolu- 40 bly mounted in said frame and provided around the circumference thereof with retaining-flaps, and a clearance bar or blade adjustably connected with the roller and adapted to bear against the same and express the wa- 45 ter therefrom and cause it to enter the receptacle, substantially as described.

20. In scrubbing-machines, the combination of a frame, brush mechanism, means for imparting reciprocatory motion thereto, a 50 roller-frame pivotally mounted upon said scrubbing-frame, a drying-roller mounted therein and driven by the same mechanism that imparts motion to the scrubbing mechanism, an adjusting-shaft provided with a 55 pawl, and arms projecting therefrom, rods connecting the drier-frame and said arms, a rack with which the said pawl is adapted to engage pivoted at one end and provided at the other end with a lateral projection, and 60 an adjusting-screw engaging said lateral projection, whereby said rack may be adjusted as desired to regulate the vertical adjustment of the roller-frame, substantially as described.

21. In scrubbing-machines, the combina- 65 tion of a frame provided with slide-rods, a brush-frame sliding thereon, said brush-frame having one end projecting laterally be-

yond the frame at one side thereof, means for imparting reciprocatory motion to said brush mechanism, a roller-frame in rear of 70 the brush-frame, a drying-roller revolvably mounted therein, and having one end projecting beyond the line of the frame at one side in line with the said projecting portion of the brush-frame, and a receptacle to receive the water and dirt taken up by the roller, substantially as described. 75

22. In scrubbing-machines, the combination of a frame provided with slide-rods, a scrubbing-board provided with brushes 80 mounted on said slide-rods, means for reciprocating the said brush-board, a roller-frame pivoted to said brush-frame, a drying-roller mounted therein and provided around the periphery thereof with flaps forming pockets, a 85 support in rear of said roller, a receptacle sliding in said support, and a clearing bar or blade extending transversely of the roller to press the water and dirt therefrom and allow the same to fall into the said receptacle, sub- 90 stantially as described.

23. In scrubbing-machines, the combination of a frame, brush mechanism mounted therein, means for reciprocating said brush mechanism, a roller-bearing frame pivotally 95 mounted upon said brush-frame, a receptacle carried thereby, a roller mounted on a shaft journaled in said frame and provided with pockets, two segment-shaped arms pivoted to the side bars of the roller-frame and carrying 100 a transverse bar or blade adapted to bear on the periphery of the roller, rods connecting said segment-arms, and means for adjusting said segment-rods, substantially as described.

24. In scrubbing-machines, the combina- 105 tion of a brush-frame, a brush-board carried thereby, means for reciprocating said brush-board, a roller-carrying frame pivoted to the said brush-frame, and provided at the rear thereof with a support, a receptacle sliding 110 in said support, a roller mounted on a shaft having bearings in said roller-frame, two seg- 115 ment-shaped arms pivoted to the side bars of said roller-frame and provided at their piv- 120 oted ends with lips, adjusting mechanism act- 125 ing on the said lips, rods connecting the two segment-arms, a transverse bar or blade car- 130 ried by said bars and adapted to act upon the periphery of the roller, and means for adjusting said bar or blade independent of the seg- 135 ment-shaped arms, substantially as described.

25. In scrubbing-machines, the combina- 125 tion of a three-sided scrubbing-frame having one of its side boards provided with a recess or cut-away portion at the lower end thereof, a bar connecting the front ends of the two side 130 bars and provided with lips or offset portions, slide-rods on the inner sides of said bars, a brush-board carrying brushes and having one side thereof provided with a lateral projec- 135 tion extending through the recess in the side bar of the frame, a spider-bearing adjustably connected with said brush-board and provided with bearing projections sliding on said rods,

a crank-shaft carrying a sprocket-wheel, a drive-shaft provided with a sprocket in connection with said crank-sprocket by a chain, a rod connecting between the said spider-bearing and crank-shaft, roller-bearing brackets at the front of the frame operating in openings therein, a cross-bar connecting the upper ends of said roller-brackets, an oscillatory shaft provided with disks operating in the said offsets on the front connecting-bar and adapted to bear against said cross-bars to lift the front end of the frame on said brackets, an adjusting-lever pivoted to the frame and provided with a pawl engaging a rack thereon, and a rod connecting said lever with the oscillatory lever, substantially as described.

26. In scrubbing-machines, the combination of a frame, brush mechanism, a drying-roller provided around its circumference with flaps forming pockets or recesses, means for adjusting the roller-frame, a removable receptacle, a pair of segment-shaped arms adjustably connected with the roller-frame, and a bar or blade carried by said arms and bearing against the periphery of said roller, said bar or blade being provided with independent adjusting means, substantially as described.

27. In scrubbing-machines, the combination of a frame, a scrubbing-board mounted therein and having one end projecting laterally beyond the frame, a crank-shaft, a rod connecting said crank-shaft and scrubbing-board, means for driving the crank-shaft, an auxiliary shaft in gear with said crank-shaft and provided with a sprocket, a drying-roller at the rear of the frame having one end projecting beyond the frame in line with the projecting end of the brush-board, said roller being mounted on a shaft carrying a sprocket-wheel, and a chain connecting the sprockets on said roller and auxiliary shafts, substantially as described.

28. In scrubbing-machines, the combination of a frame, a scrubbing-brush having one end projecting laterally beyond said frame, a crank-shaft, a drive-shaft imparting motion to said crank-shaft, a connecting-rod pivoted to the brush-board and detachably connected with the crank-shaft, an auxiliary shaft in gear with and driven by said crank-shaft, said auxiliary shaft being provided with a sprocket having suitable clutch connections, a roller-frame pivoted to the brush-frame in rear thereof, a drying-roller mounted on a shaft having bearings in said frame, and provided around its circumference with retaining-pockets, said roller-shaft being provided with a sprocket, a chain connecting between the said sprockets of the roller and auxiliary shafts, a pan or receptacle supported by the roller-frame in rear of the roller, two segment-shaped arms pivoted to the side arms of the roller-frame, a clearing bar or blade adjustably connected with the said arms to bear against the periphery of the roller, a shaft on the handle of the machine and provided with arms, rods connecting between said arms and the side bars of the roller-frame, a segment-rack pivoted at one end to the handle-frame and provided with rack-teeth and a lateral extremity at the other end, a pawl on a shaft adapted to engage with said rack-teeth, and an adjusting-screw adapted to bear against the said lateral extremity of the segment-rack and adjust the same vertically to regulate the vertical adjustment of the roller-frame, substantially as described.

In testimony whereof I have signed this specification in the presence of two subscribing witnesses.

SAMUEL J. CLISE.
